UNITED STATES PATENT OFFICE.

CHARLES R. HUDSON, OF GREEN BAY, WISCONSIN, ASSIGNOR OF ONE-HALF TO DAVID W. HUDSON, OF GREEN BAY, WISCONSIN.

PUMPING APPARATUS.

1,077,474.

Specification of Letters Patent. Patented Nov. 4, 1913.

Application filed April 14, 1911. Serial No. 621,091.

To all whom it may concern:

Be it known that I, CHARLES R. HUDSON, a citizen of the United States, residing at Green Bay, county of Brown, and State of Wisconsin, have invented new and useful Improvements in Pumping Apparatus, of which the following is a specification.

My invention relates to improvements in pumping apparatus.

10 The object of my invention is to provide improved form of apparatus, especially suited for use in tubular wells, and in which water will be delivered continuously on both strokes of the piston.

15 In the following description, reference is had to the accompanying drawings, in which—

Figure 1 is a vertical sectional view of portions of a tubular well showing my invention as it appears in position of use therein. Fig. 2 is an elevation, with the pump cylinder or barrel and well casing omitted.

Like parts are identified by the same reference characters in both views.

My improved pumping apparatus is designed to be suspended in a tubular casing 1. The cylinder or barrel is formed in sections 2 and 3, which are secured together by 20 a connecting member 4. A piston rod 5, which may be solid at its upper end, is provided with a tubular section 6. The member 6 is connected to the member 5 by a coupling 9 having ports 10 through which water may 25 pass from member 6 into the upper cylinder section 2. The member 4 is screw threaded at its respective ends to receive the cylinder sections 2 and 3, and the intermediate portion has its inner surface conically tapered 30 to receive a tapered plug 10' through which the tubular piston rod section 6 passes, suitable packing being provided at 11 to prevent leakage. The central portion of the member 4 is provided with apertures 13, 35 communicating with inwardly and downwardly extending ports 15 in the plug 10', said ports extending through the lower end portion of the plug 10' and being normally closed by a ring valve 17, which encircles 40 the piston rod section 6 and is normally supported in closed position by a spring 19 suspended from plug 10' by a supporting

member 20. The walls of said supporting member are suitably apertured at 21 to permit water to pass into cylinder section 3 55 when the valve 17 is opened.

The lower end of piston rod section 6 connects with a valve casing 25, to which a piston 26 is secured, said piston having cup leathers 27 and 28, the outer margins of 60 which turn upwardly and downwardly respectively along the walls of the cylinder section 3. The piston 26 is provided with a central port 30, extending through the piston and the valve casing 25, a valve 31 being 65 seated on the upper end of the piston member and normally held to its seat by gravity. The valve casing 25 is provided with ports 35 leading inwardly from the cylinder section 3 to the interior of the valve casing and 70 normally closed by an annular valve 37 having a central port 39 therein, communicating through the upper end of the passage or port 30 with the interior of piston rod section 6. Valve 37 is normally held to its 75 seat by a spring 40, which spring is seated upon the upper end of the piston member 26.

The lower end of the cylinder section 3 is provided with a coupling member 43, secured thereon and having an internally screw threaded lower end portion 44 adapted to receive a suction pipe. This member 43 also has its central portion internally tapered to receive a valve seat 45 upon 80 which a downwardly closing valve 46 is mounted. The valve seat 45 is provided with ports 49 normally closed by the valve 46. The valve seat 45 is also provided with an upwardly projecting member 50 having 85 a flanged projection 51 near its upper end, between which, and the valve 46, a coiled spring 52 is located, to insure the closing of said valve 46. The upper end of the member 50 is tapered and screw threaded as 90 shown at 55, and is adapted to engage in the internally screw threaded lower portion of the passage 30 in piston 26, whereby an extreme downward movement of the piston 26 followed by a rotation thereof, will cause 95 piston 26 to engage member 55, so that said member 55, together with the valve seat 45 and valve 46, may be removed with the piston, as illustrated in Fig. 2.

In operation, the upward movement of piston 26 will draw water past the valve 46 into the lower portion of cylinder 3. A downward movement of piston 26 will then 5 force this water upwardly through the passage 30 past valve 31 and through piston section 6 and ports 10 into the upper cylinder section 2. Said downward movement of the piston 26 will also draw water 10 through the openings 13 and ports 15 past the valve 17 into the upper portion of cylinder section 3, this water being discharged from cylinder section 3 past valve 37 into 15 passage 30 and piston rod section 6 on the next up-stroke of piston 26. It is therefore obvious that there will be a constant flow of water through piston rod section 6, so long as the movement of piston 26 continues in either direction, said water being delivered 20 from the lower portion of cylinder section 3 on the down stroke, past valve 31, and from the upper portion of section 3 on the up stroke, past valve 37.

My improved construction is particularly 25 adapted for deep wells, since it permits a multiplication of piston rod sections 3 and pistons, limited only by the strength of the materials used. For example, a duplicate 30 connecting member 4 and plug 10 may be employed at the lower end of cylinder section 3 in substitution for the member 43 and valve seat 45. Another cylinder section 3, piston 26, and valve casing 25, with valves 31 and 37 therein, may then be connected 35 to the lower end of the duplicate connecting member 4, such valve casing and piston being supported from the piston 26 illustrated in Fig. 1, by a duplicate tubular piston rod section 6. The member 43 with valve 40 seat and valve, would, of course, then be adjusted to the lower end of the lower or 45 duplicate cylinder section 3. It is not deemed necessary to illustrate such duplication of the parts of my pumping apparatus, the manner of such duplication being obvious from the above description and involving the mere addition of another cylinder section 3 and a duplication of the 50 parts shown in Fig. 2 therein.

Having thus described my invention, what I claim as new, and desire to secure by Letters Patent, is—

1. A pumping apparatus comprising the combination with a set of cylinder sections, 55 connected together and provided with a ported plug at the point of connection, of a tubular piston rod extending through said plug, a piston supported by said tubular piston rod and operating in one of the cylinder sections, said piston having a valved 60 passage leading therethrough, a valve casing mounted on said piston and ported at its upper end at the sides of the piston rod, a valve controlling the delivery of fluid to

the tubular piston rod from below the piston, a spring actuated valve controlling the delivery of fluid to the tubular piston rod through the upper ports in the valve casing from above the piston, a valve controlling the admission of fluid through said ported 65 plug to the space above the piston, a coiled spring normally closing said valve, a supporting member therefor connected with the ported plug, and another valve controlling the admission of fluid from below the lower 70 cylinder section to the space below the piston. 75

2. A pumping apparatus comprising the combination of a set of cylinder sections, a connecting member therefor, a tapered plug seated in said connecting member and provided with inlet ports, said connecting member being provided with apertures in registry with said ports, a spring seated 80 check valve permitting the delivery of fluid to the lower cylinder through said ports, a tubular piston rod extending through said plug, a ported piston, a valve casing connecting the same with said piston rod, a check valve permitting an upward delivery of fluid through the piston port into 85 said casing, another check valve permitting a downward delivery of fluid from the cylinder space above the piston into the valve casing, the interior of said valve casing being in communication with the tubular piston rod section, and a check valve adapted to admit fluid to said cylinder section below the piston. 90

3. A pumping apparatus comprising the combination of a set of cylinder sections, a 100 tapered and ported connecting member therefor, a plug seated in the connecting member and provided with downwardly extending valved passages leading from the connecting member ports through the plug 105 into the lower cylinder section, a check valve at the lower end of said cylinder section, a two way acting piston in said cylinder section provided with a port extending upwardly therethrough, a valve casing 110 mounted upon said piston, a check valve in said casing permitting fluid to enter the casing through the piston port from below the piston, another check valve admitting fluid to said casing from above the piston, 115 a tubular piston rod connected with said casing and in communication with the interior thereof, said tubular piston rod extending through said ported plug and communicating with the interior of the upper cylinder section above the plug. 120

4. A pump piston provided with a passage therethrough, a tubular piston rod with which said passage communicates, a downwardly closing valve seated in said 125 passage and controlling the flow of fluid therethrough from below the piston, and an upwardly closing valve seated in said pas-

sage and controlling the admission of fluid thereto from the space above the piston exterior to the piston rod, said upwardly closing valve being adapted, when closed, to 5 permit a delivery of fluid to the tubular piston rod, said passage being enlarged to receive the valves and said valves being provided with interlapping guide members, to-

gether with a spring for seating the upper valve.

In testimony whereof I affix my signature in the presence of two witnesses.
